UNITED STATES PATENT OFFICE.

FRED A. PUTNAM, OF MELROSE, MASSACHUSETTS, ASSIGNOR TO MARKEM MACHINE COMPANY, OF BOSTON, MASSACHUSETTS, A CORPORATION OF MASSACHUSETTS.

MACHINE FOR EMBOSSED OR MARKING LEATHER.

1,108,518.

Specification of Letters Patent.

Patented Aug. 25, 1914.

Application filed February 2, 1911. Serial No. 606,117.

To all whom it may concern:

Be it known that I, FRED A. PUTNAM, a citizen of the United States, residing at Melrose, county of Middlesex, State of Massachusetts, have invented an Improvement in Machines for Embossing or Marking Leather, of which the following description, in connection with the accompanying drawing, is a specification, like letters 10 on the drawing representing like parts.

This invention relates to machines for embossing or marking leather and the selected embodiment of the invention which is herein illustrated has been particularly 15 designed for making a gold or gilt impression on leather.

The features wherein the invention resides will be more fully hereinafter described and then pointed out in the appended claim.

Referring now to the drawings, Figure 1 is a side view of the upper part of a machine embodying the invention; Fig. 2 is a section on the line $y-y$, Fig. 1; Fig. 3 is a 25 front view of Fig. 1; Fig. 4 is a section on the line $x-x$, Fig. 1. Fig. 5 is a view showing a bed provided with a horn instead of with a platen.

30 3 designates a standard or frame which carries at its upper end a head 4 in which operates a vertically-moving plunger 5 which carries the type or embossing dies. This plunger may be given its vertical movement by any suitable mechanism, one 35 simple device being the toggle-lever arrangement 6 which is connected by the link 7 with an eccentric 8 on the shaft 9. The shaft 9 is shown as provided with a gear 10 which meshes with and is driven by a pin- 40 ion 11 on a driving shaft 12, and any suitable clutch mechanism may be employed for controlling the rotation of the shaft 9. I will preferably employ some suitable one-revolution clutch mechanism which will 45 permit the shaft to make a complete rotation, and will then cause it to be brought to rest in the position shown in Fig. 1 with the plunger 5 elevated. The clutch is operated by a suitable link 13 which is connected to 50 a treadle. This clutch and the operating mechanism for the plunger form no part of my invention and may be of any suitable character. The plunger is shown as having the forked portion 14 between the arms 55 of which the die or type holder 15 is sup-

ported. In the present embodiment of the invention this die-holder 15 is arranged to support a plurality of dies or sets of type, and it is rotatably mounted in the fork 14 so as to permit any one of the dies to be brought into operative position. It is herein shown as provided with four faces 16 on each of which a die member or type carrier 17 may be sustained, said members 17 having on their faces type or embossing 65 projections 18 shaped to make the proper imprint upon the goods.

As herein shown the die holder 15 is provided with trunnions 19 which are rotatably mounted in the arms of the fork so that any one of the die members or type carriers can be brought into operative position. The holder 15 is held in its adjusted position by means of a spring catch 20 which engages in any one of a plurality of apertures in one 75 end of the holder. The die members 17 are preferably removably sustained in the carrier 15 so that die members having different dies or type thereon may be used. As herein shown each die member is provided 80 with a stem 21 which enters a radially-arranged socket in the holder, each stem being provided with a notch 22 in which is received the end of a spring-pressed locking pin 23 carried by the holder. This is a 85 convenient way of removably supporting the die members in the holder 15.

The standard 3 has extending therefrom a bed member 220 on which is sustained a platen or work holder 230, the latter being 90 for the purpose of supporting the work while the impression is being made. The platen 230 is mounted to move transversely to the direction of movement of the die holder thereby to bring the work-supporting 95 portion of the platen underneath the die or to carry it out from beneath the die and means are provided whereby during this reciprocating movement of the platen the type or dies are inked.

100 As herein shown the bed member 220 is provided with the dove-tailed rib or guide-way 24 on which the platen 230 is mounted to slide, and I have herein shown the platen as provided with the arm 25 adapted to engage the two stop pins 26 which extend laterally from the bed and by which the reciprocating movement of the platen is limited.

105 The ink is applied to the type by means of an inking roll 270 which is carried by and 110

moves with the platen 230 so that when the platen is withdrawn into the dotted line position Fig. 1 to receive a fresh piece of work, the inking roll will be carried under and 5 against the type thereby inking the latter. In the present embodiment, the inking roll is rotatably mounted in two standards 27 which are provided with stems 28 that are supported in bosses 29 formed on the platen, 10 said stems being arranged to have vertical movement in the bosses, springs 30 surrounding the stems being employed for yieldingly holding the standards in their elevated position. The reason for making 15 the standards yielding is to permit the inking roll to yield slightly as it passes under the type 18. The bed 220 carries a rotatable inking plate 31 on which the ink is placed and from which it is transferred to the inking roll. Said plate is mounted to be turned 20 slightly at every reciprocation of the platen, and is situated so that the inking roll will roll over it as the platen is moved. In this way any ink which is applied to the plate 31 25 will be uniformly spread over its surface and applied to the inking roll and the roll will be freshly inked each time that the platen reciprocates.

To provide for intermittently turning the 30 plate 31, I have provided a ratchet wheel 32 which is rigid with the plate and is situated to be engaged by a pawl 33 carried by the platen so that upon each backward movement of the platen the plate will be given a 35 slight turning movement. The construction is such that the turning of the plate will be accomplished while the roll is in contact therewith.

The plate 31 may be rotatably mounted in 40 the bed 220 in any suitable way. As herein shown said plate has depending therefrom a pivotal shaft 34 which is supported in a bearing 35 carried by the bed and which rests on an adjusting screw 36 by means of 45 which the plate may be adjusted vertically.

The bed 220 is mounted for vertical adjustment so as to permit the platen to be positioned properly for different thicknesses of work. As herein shown said bed is mounted 50 to slide vertically on a dove-tailed guide 37 formed on the standard 3 and it is adjusted by means of an adjusting screw 38 which extends loosely through a boss or bearing 39 projecting from the standard and has a hand 55 wheel 40 screw-threaded thereonto. This adjusting screw 38 carries a collar or nut 41 above which is situated a spring 42 that is confined between the bed and the nut or collar. The spring allows a certain yielding 60 movement to the bed while the bed can be adjusted vertically by turning the hand wheel.

The operation of the device will be readily understood from the foregoing and is as 65 follows: The platen 230 is pulled outwardly

by hand, during which movement the inking roll 270 passes under and inks the type or embossing die 18. When the platen is in the dotted line position the work-supporting portion thereof is withdrawn from under the die holder so that the work to be printed or embossed may be readily placed thereon. When the work is properly positioned the platen 230 is moved back into the position shown in Fig. 1; during the first part of 70 which movement the roll again engages the die 14 and during the last part of which movement the inking roll rolls over the plate 31 which is simultaneously turned, thereby giving the inking roll a fresh supply of ink. When the parts are in the position shown in full lines Fig. 1, the work is properly positioned under the die 18 and the driving mechanism is set in operation thereby causing 75 the die to be depressed into engagement with the work thereby to imprint or emboss the latter.

The machine herein illustrated is especially designed for imprinting the name of the manufacturer, or name of the shoe, or 80 some other identifying mark in gilt letters on the inside of the shoe upper, and to do this I propose to use a gilt or gold ink, and in order to make a lasting impression I find it is desirable to heat the dies while they are 85 acting on the work. I have accordingly provided means whereby the die holder and dies carried thereby may be properly heated. As one convenient means for accomplishing this, I provide the die holder with a cavity 90 extending centrally thereof in which is placed an electric heater 45 which is connected to and controlled by a suitable switch 46 to which the conductor cords 47 extend. The switch 46 may be of any suitable variety adapted to turn the current off from or on to the electric heater 45, and the heater 45 may be of any usual construction adapted 95 to accomplish the desired object. I find that where the die is heated in this way it is 100 possible to use ordinary gold paint for the ink with which to make the impression, that is paint which is formed by mixing a bronze or gold powder with a proper oil or other liquid vehicle. Where this gold paint is 105 used, the ink-distributing plate 31 is important because inking material of this nature dries and hardens very quickly and said plate forms an efficient device for keeping the ink stirred and preventing the gold 110 powder from separating from the oil or other liquid vehicle. Under some circumstances it may be desirable to merely burn the impression into the sole of a shoe, and this can be accomplished with my machine by using 115 the work support shown in Fig. 5. This work support comprises a body 60 which is to be substituted for the bed 220. This body has a horn 61 extending therefrom over 120 which the shoe may be placed so as to bring 125

the sole in proper position to receive the impression from the type.

Having fully described my invention, what I claim as new and desire to secure by 5 Letters Patent is:—

In a device of the class described, the combination with a stand having an overhanging head, of a plunger movable vertically in said head, a die-holder sustained by the 10 plunger, a bed extending laterally from the stand, an inking plate rotatably mounted in the bed, a platen slidably mounted horizontally on said bed, two standards sustained by said platen, an inking roll carried by the 15 standards, springs for yieldingly holding the

standards in elevated position, a projection extending laterally from the stand, an adjusting screw extending loosely through the projection and carrying a nut, a spring confined between the nut and the bed for yieldingly supporting the latter, and means for rotating the nut whereby the bed may be raised or lowered. 20

In testimony whereof, I have signed my name to this specification, in the presence of 25 two subscribing witnesses.

FRED A. PUTNAM.
